UNITED STATES PATENT OFFICE

2,546,945

ILLUMINATED EARRING

Eli W. Gaffield, Washington, D. C., assignor of fifty per cent to Raymond N. Matson, Silver Spring, Md.

Application October 3, 1947, Serial No. 777,672

3 Claims. (Cl. 240—64)

1

The present invention relates generally to improvements in ear-rings and more particularly to means including ornamental members for illuminating the ear-rings.

The chief object of the present invention is to provide a highly decorative pair of ear-rings which may be illuminated at will by the wearer to enhance its decorative effects.

Another important object of the present invention is to provide a pair of ear-rings which may be readily illuminated by concealed means supported in the hair of the wearer.

A further important object of the present invention is to provide a pair of ear-rings which are adapted to be illuminated by a small battery connected in a parallel electrical circuit with the ear-rings.

A still further important object of the present invention is to provide a novel circuit breaking means for the electrical circuit of a pair of battery illuminated ear-rings.

Another object of the present invention is to provide a pair of ear-rings which are adapted to be illuminated by electrical means mounted in the hair of the wearer and concealed by decorative members.

Another object of the present invention is to provide a self-contained novelty of the type described which is simple in construction, may be inexpensively manufactured, and which will be of long life, the various parts being susceptible of ready replacement.

Other objects and advantages of the invention will become apparent during the course of the following description.

In the drawing I have shown one embodiment of the invention.

Figure 1 is a view of the invention mounted on the head and ears of a wearer;

Figure 2 is a view showing the various components of the invention and the electrical circuit connecting the same;

Figure 3 is a fragmentary view in side elevation to an enlarged scale of the circuit breaking means mounted on the battery; and

Figure 4 is a vertical sectional view thereof, taken on the line 4—4 of Figure 3.

Referring now to the drawings, numeral 10 designates a woman's comb which is conventionally arcuate in cross-section to conform to the shape of the head. A small dry-cell battery 12 of the pencil type is secured at spaced points to the upper portion of the comb 10 by wiring 14, etc. so as to be supported thereby.

In order that the comb and battery may be 55 (Figure 3) to a position against the strap end 42

2

concealed when placed in the hair of a wearer as shown in Figure 1, a colorful bow or ribbon 16 of conventional material is also secured to the comb 10. This bow 16 may be formed of plastic or any light gauge metal if desired as long as it effectively and decoratively conceals the presence of the comb 10 and battery 12 in the wearer's hair.

The ear-rings 20 are identical and each comprises a small internally threaded socket 22 made integral with a reflector or decorative jewel 24. A small incandescent bulb 26 is inserted through an aperture in the reflector 24 where it is retained in screwthreaded engagement with the socket 22. It will be readily apparent that the bulb 26 may be of any chosen color so as to enhance the decorative effect of the jewel 24 to a maximum by its illumination. The selection of a particular type of jewel or reflector is also guided by the decorative effect which the wearer desires to achieve.

The ear-rings 20 are each provided with a conventional ear-lobe clamp 28 which may be fixed either to the jewel 24 (as shown) or to the socket 22. Each socket is electrically connected to the battery 12 in a parallel circuit by means of insulated wires 30 and 32 which are preferably of a neutral color so as to blend with the hair of the wearer if exposed.

The wires 30 which lead to the positive pole of the battery terminate in a copper strap 34 which is suitably secured to the cardboard insulating tube 36 surrounding the battery. The strap 34 terminates in an inverted U contact 38 which makes electrical connection with a partially overlying and cooperating strap 35 which is also mounted on the tube 36 and has a direct connection with the positive battery pole. Thus parallel electrical circuits are established with 40 the ear-rings, the current passing from the positive battery pole, the straps 35 and 34, the wires 30, the socket 22, the bulb 26, and back to the battery case by the wires 32.

Novel means for breaking the previously described circuits is provided by a slide 40 which tracks on the strap 35 by means of down and inwardly turned flanges 41 which loosely grip the strap 35 and is prevented from disconnection therewith by the upturned strap end portion 42. The slide 40, which may be formed of any suitable insulating material such as wood, plastic, etc. is effective to break the electrical circuit when moved from the position shown 50 to a position against the strap end 42

where the under side of the slide engages the contact 38 to separate the straps 34 and 35.

An important advantage of the present invention resides in the facility with which damaged or worn parts may be replaced. Defective or different types and shapes of incandescent bulbs are of course readily removable from or secured in the screw threaded sockets 22. Jewels or reflectors may be substituted one for another by simple soldering operations which may readily be performed by any jeweler. Similarly, a dead battery may be replaced by removing the cell from the tube 36, and inserting a new battery in the old tube. The soldering to the new cell of the ends of the wires 32 and the strap end 35 may also be readily done by a jeweler, etc., the switch blade connections remaining undisturbed.

It will now be apparent that the ear-rings comprising the present invention are simple but unique in construction and operation and provide a highly decorative effect when worn on the head for artistic, display or amusement purposes.

It is to be understood that the form of my invention herewith shown and described is to be taken as a preferred example of the same and that various changes in the shape, size and arrangement of parts may be resorted to without departure from the spirit of the invention or the scope of the subjoined claims.

I claim:

1. A hair mounted ear-ring device including a member for positioning on the ear lobe of a wearer comprising a socket, a reflector mounted on said socket, an incandescent bulb mounted in said socket, and means for energizing said bulb to illuminate said ear-ring, said means comprising a comb for positioning in the hair of the wearer, a battery fixed to said comb and supported thereby, and wires connecting said bulb and said battery to form an electric circuit therefor.

2. An ear-ring device including a member for positioning on the ear lobe of a wearer comprising

5 a socket, a reflector mounted on said socket, an incandescent bulb mounted in said socket, and means for energizing said bulb to illuminate said ear-ring, said means comprising a comb for positioning in the hair of the wearer, a battery fixed to said comb and supported thereby, wires connecting said bulb and said battery to form an electric circuit therefor, and decorative means fixed to said comb for concealing the battery and its supporting comb when positioned in the hair of a wearer.

10 3. An ear-ring device including a member for positioning on the ear lobe of a wearer comprising a socket, a reflector mounted on said socket, an incandescent bulb mounted in said socket, and means for energizing said bulb to illuminate said ear-ring, said means comprising a comb for positioning in the hair of the wearer, a battery fixed to said comb and supported thereby, wires connecting said bulb and said battery to form an electric circuit therefor, normally closed switch blades mounted on said battery, and insulator means mounted on one of said blades and operable for separating the same to open said circuit.

25 ELI W. GAFFIELD.
